INCLOSURE FOR RADIATORS

Frank E. Seeley, Rye, N. Y., assignor to American Radiator Company, New York, N. Y., a corporation of New Jersey

Application June 5, 1931, Serial No. 542,286

13 Claims. (Cl. 237—79)

My invention relates to improvements in inclosures for radiators and other analogous structures, and the same has for its object to provide an inclosure which is simple in construction, efficient in operation, and which may be readily applied to a radiator.

Further, said invention has for its object to provide an inclosure which is readily adaptable to radiators of different lengths, i. e. consisting of a larger or smaller number of sections.

Further, said invention has for its object to provide an inclosure or casing consisting of end members having their edges engaging two adjacent end sections of a radiator and bridging the space between the said two adjacent sections in order to hold the end inclosure member duly positioned upon and secured to the radiator.

Further, said invention has for its object to provide an inclosure or casing consisting of two substantially U-shaped end members having the vertical edges of each member engaging the opposing faces of two adjacent radiator sections and completely bridging the interval or space between these sections.

Further, said invention has for its object to provide a radiator inclosure or casing in which the openings affording access to the interior thereof, and to the control means for the radiator are provided with covers having means for simultaneously properly positioning the same over the openings and securing the same to the inclosure.

Other objects will in part be obvious and in part be pointed out hereinafter.

To the attainment of the aforesaid objects and ends, my invention consists in the novel details of construction, and in the combination, connection and arrangement of parts hereinafter more fully described and then pointed out in the claims.

In the accompanying drawing—

Figure 1 is a front view showing a radiator showing one form of inclosure or casing constructed according to and embodying my said invention applied thereto;

Fig. 2 is an enlarged detail horizontal section of one of the end members of the inclosure on the line 2—2 of Fig. 1;

Fig. 3 is an enlarged detail vertical section on the line 3—3 of Fig. 1;

Fig. 4 is an enlarged detail section on the line 4—4 of Fig. 1 showing the manner in which the ends of the front member are disposed within the end members of the casing;

Fig. 5 is a similar view of the same parts on the line 5—5 of Fig. 1, and

Fig. 6 is a perspective view showing the same parts seen in Fig. 5.

In said drawing 10 designates a radiator of well-known general form comprising a plurality of sections arranged side by side in spaced relation and communicatively connected at their upper and lower ends.

11 denotes an inclosure or casing formed of sheet metal and comprising two vertical end members 12, 12 of channel or substantially U-shape in cross-section each having its free inner edges turned inward, forward, and again inward to form two flat surfaces 13, 13^a disposed at right angles to the longitudinal axis of the radiator, and united by an intervening web portion 14 whose width is substantially equal to the distance between the opposing inner faces of two adjacent end sections of the radiator. The free inner edges of the end members 12 form a constricted open inner end portion.

Each end member 12 is provided in its front wall at its lower edge, with a cold air inlet opening or recess 15, and above said inlet 15 with two superposed openings 16, 16^a for affording access to the interior of said end member and the valves and piping therein.

The openings 16, 16^a are each provided with a cover plate 17 of greater outline than said openings 16, 16^a. Each cover plate is provided upon its outer side near its center with a knob 18, and upon its rear side near its lower edge and at a point about midway of its height with inwardly and downwardly inclined members 19 which are slightly tapered with their upper wider portions corresponding substantially in width with the width of the openings 16, 16^a, so that when the members 19 are inserted into said openings 16, 16^a, and the cover plates permitted to drop into place the said members 19 will automatically position said cover plates with respect to said openings 16, 16^a, and tend to draw said cover plates inwardly against the outer surfaces of the casing members 12 by the engagement of said inclined members 19 with the lower, end edges of the openings 16, 16^a.

20 denotes a front plate which may be of any desired height and consist of either a solid or perforated plate of sheet metal. In the present instance the said front plate is shown covering only the lower front portion of the radiator 10, and having a longitudinal recess or opening 21 therein for the admission of cold air to the interior of the casing and the rear portion of the radiator. To secure the front plate 20 in position the inner opposing edges of the casing mem-

bers 12, are provided close to their front wall portions, with vertical slots 22 to receive the ends of said front plate. To prevent longitudinal movement of said front plate and to hold the same 5 duly positioned between the end members 12 of the casing said front plate 20 is provided at its upper edge with an inwardly turned bead or hem 23 whose ends terminate inwardly of the opposite vertical edges of said front plate 10 and form stops against which the inner wall portions of the end members 12 abut.

24 denotes a cover extending over the top of the radiator 10 and end members 12. The cover 15, preferably, has its top perforated to permit of the escape of heated air, and along its edges it is provided with a depending flange 25. The flange portion at the rear of the cover 24 is flat and engages the rear wall portions of the end members 12 of the casing 11, and the front and 20 end portions of said flange 25 are turned inward and then downward at 26 and have their depending portions 26 closely embracing the front and end walls of the end member 12.

It is to be noted that my invention provides an 25 inclosure which may be readily adapted to radiators of different lengths since the end members 12 merely require a front member 20 and a cover 24 of appropriate length to form the complete inclosure.

30 Having thus described my said invention, what I claim and desire to secure by Letters Patent is: 1. The combination of a radiator including a plurality of sections arranged side by side in spaced relation with an inclosure therefor including two vertical channel members of substantially U-shape in cross section and each having its free vertical edges turned inward, then lengthwise of the radiator, and again inward and said two inwardly-extending faces in engagement with two adjacent end sections of the radiator.

35 2. The combination of a radiator including a plurality of sections arranged side by side in spaced relation with an inclosure therefor including two vertical channel members of substantially U-shape in cross section and each having its free vertical edges turned inward, then lengthwise of the radiator, and again inward and said inwardly-extending faces slidably engaging two of the end sections of the radiator, and a 40 cover extending over the radiator and embracing said channel members.

3. An inclosure for radiators comprising a casing having a plurality of superposed openings therein, a cover therefor larger than said openings and means on said cover engaging the corresponding edges of said openings and constructed and arranged to position said cover vertically and horizontally with respect to said openings and to secure said cover to said casing.

40 4. An inclosure for radiators comprising a casing having a plurality of openings arranged vertically in alignment, a cover therefor larger than said openings and means on said cover simultaneously engaging the lower edges of said openings and constructed and arranged to position said cover vertically and horizontally with respect to said openings and to secure said cover to said casing.

45 5. An inclosure for radiators comprising a casing having a plurality of openings arranged in vertical alignment, a cover therefor larger than said openings and means on the rear side of said cover engaging the lower edges of said openings and constructed and arranged to draw said cover inwardly and hold the same in position vertically

and horizontally over said openings and against the outer side of said casing.

6. An inclosure for radiators comprising a casing having a plurality of openings arranged in vertical alignment, a cover therefor larger than 50 said openings, and inclined members on the rear of said cover coextensive in width with the width of said openings and extending rearwardly and downwardly, and engaging the lower edges of said openings and constructed and arranged to position said cover vertically and horizontally with respect to said openings and to hold said cover secured to said casing.

7. The combination of a radiator having a plurality of connected sections with an inclosure 90 therefor including a pair of vertical channel members each cooperating with certain of the end sections of the radiator, each channel member having along each of its vertical edges a plurality of vertical end portions arranged transversely of the radiator and engaging with the opposing transverse sides of two adjacent sections of the radiator, and an intervening web portion uniting said vertical end portions and bridging the space between said adjacent radiator sections. 95

8. The combination of a radiator having a plurality of sections arranged in spaced relation side by side with an inclosure therefor including vertical channel members each having its free vertical edges terminating in a plurality of vertical 100 connected portions arranged transversely of the radiator and slidably engaging the opposing transverse sides of the adjacent end sections of the radiator.

9. The combination of a radiator including a 105 plurality of sections arranged in spaced relation side by side with an inclosure therefor including vertical channel members each having its free vertical edges terminating in a plurality of vertical 110 portions disposed transversely of the radiator, and an intermediate web portion uniting said vertical portions; said vertical connected 115 portions slidably engaging the opposing transverse sides of the adjacent end sections of the radiator, and said intermediate web portion 120 bridging the space between said two sections.

10. The combination of a radiator having a plurality of spaced sections with an inclosure 125 therefor comprising vertical channel members each having the marginal portions thereof turned inwardly between two adjacent sections of the radiator in interlocking engagement therewith, and a longitudinal member extending across the front of the radiator at the base thereof and through the contiguous inwardly turned 130 portions of the channel members.

11. The combination of a radiator having a plurality of spaced sections with an inclosure 135 therefor comprising vertical channel members each having the margins thereof turned inwardly in interlocking engagement with adjacent end sections of the radiator, the lower ends of the inturned portions being provided with vertical slots, and a longitudinal member extending across the radiator at the front and into said slots, and 140 having portions abutting said inturned portions contiguous to said slots for preventing longitudinal movement of said last named member.

12. The combination of a radiator having a plurality of spaced sections supported in spaced 145 relation to the floor with an inclosure therefor comprising vertical channel members each having the margins thereof turned inwardly between adjacent end sections and then angularly in interlocking engagement with the opposing sides 150

of said adjacent end sections, the inturned portions at the front of the radiator having slots therein extending vertically from the lower edges of said inturned portions, and a member extending across the front of the radiator at the base thereof and into said slots to be retained in vertical position by said inturned portions while supported on edge by the floor, said last named member including portions abutting said inturned portions to prevent longitudinal movement of said last named member relative to said channel members.

5 10 15 20 25 30 35 40 45 50 55 60 65 70 75

plurality of sections arranged in spaced relation side by side with an enclosure therefor including vertical channel members each extending over the vertical edges of certain of the adjacent sections, the margins of each of said channel members including inwardly bent portions in engagement with the inner side of an outer section, and portions angularly related to said inwardly bent portions extending across the space between opposing sections into engagement with the inner side of the next adjoining section.
